STRIP FOLDER FOR SEWING MACHINES AND THE LIKE

Filed May 28, 1936

FIG. I.

INVENTOR:
Charles S. Thompson,
BY *Fally & Dow*
ATTORNEYS.

UNITED STATES PATENT OFFICE

2,175,493

STRIP FOLDER FOR SEWING MACHINES AND
THE LIKECharles S. Thompson, Elmhurst, Ill., assignor to
Union Special Machine Company, Chicago, Ill.,
a corporation of Illinois

Application May 28, 1936, Serial No. 82,189

6 Claims. (Cl. 112—138)

This invention relates to devices useful in connection with sewing or looping machines and the like for folding strip material incident to guiding it to the stitching or looping instrumentalities 5 for attachment to the edges of a body fabric, as for example, in finishing underwear and other garments. Certain forms of tape or strip material, particularly when of relatively thin knitted fabric, are difficult to control in folding due to 10 the tendency of the fabric to curl at the edges with the result that the folding is often uneven and the garments defective from the standpoint of finish and appearance.

The aim of my invention is to obviate the 15 above difficulties, which objective I realize in practice as hereinafter more fully disclosed, through provision of a folder of simple construction having at its delivery end smoothing elements with lips to cooperate with retroverting edges about which the strip margins pass after 20 the folding for directional change in the travel of the strip, in effectively eliminating the edge curl in the material so that the margins are presented perfectly flat to the seaming or looping instrumentalities, said smoothing elements being in the 25 form of spring tongues capable of yielding to permit passage of irregularities in the strip, and moreover, capable of adjustment so that the folder can be adapted to strip material of different thicknesses.

In the attached drawing,

Fig. I is a fragmentary plan sectional view of the frontal portion of a sewing machine fitted with my improved strip folder and guide.

Fig. II is a perspective view of the folder with portions thereof broken out and in section.

Fig. III is a perspective view of the delivery end of the folder drawn to an enlarged scale, and

Fig. IV is a detail sectional view taken as indicated by the arrows IV—IV in Fig. III.

With more detailed reference, first more particularly to Fig. I of these illustrations, I designates the base or work support of the sewing machine into which is set a removable plate 2 with a 45 slot 3 in which the toothed portion 4 of a feed dog operates, said feed dog being actuated in a well known manner by means (not shown) beneath the work support. The machine is in this instance provided with two needles 5, which are 50 actuated by suitable mechanism (not shown) from above the work support 1, by cooperation with suitable looper mechanism (not shown) beneath said work support, and produce a cover seam C whereby the finishing strip indicated at 55 S is secured to a body fabric F as the latter is

progressed crosswise of the work support 1 under the action of the feed dog 3.

The strip folder with which the present invention is directly concerned is comprehensively designated by the numeral 6 in the several views of the drawing, and as shown, is fashioned from sheet metal to the form of a horizontally elongate tube which merges from flat vertical cross-sectional configuration at its right end or receiving end into transverse U-shaped cross-sectional configuration toward its left hand or delivery end, where it is formed with a short lateral guide extension 7, also of U-shaped cross section. To the back of the folder 6 is permanently secured a vertically slotted plate 8 which slidably engages the upstanding tongue 9 of a fixed bracket 10 on a supporting arm 11 attached to the work support 1, so that the folder may be adjusted up and down relative to the work support 1. A screw 12 serves as a means for securing the folder 6 after it has been properly adjusted. The delivery end of the folder 6 is finished off at a bevel with resultant provision of two spaced retroverting edges 13 at an angle to the longitudinal about which the strip margins pass, after folding of the strip S for change in the direction of travel of said strip by way of the guide extension 7 enroute to the needles 5 of the sewing machine as shown in Figs. I and III.

For the purpose of flattening the strip margins and eliminating edge curls in them, the folder 6 is provided at the top and bottom of its delivery end with smoothing elements in the form of spring tongues 15 which are reverse duplicates of each other. The rear ends of the smoothing elements 15 are secured to anchorage projections 16 on the folder by screws 17, and their free or forward ends are finished off at a bevel and formed with lips 18 which extend parallel with the retroverting edges 13 of said folder, i. e. 30 transversely of the direction of travel of the strip at the regions of contact therewith. By aid of set screws 19 threadedly engaged in the smoothing elements 15 near their free ends and bearing against the corresponding sides of the folder 6, 35 said elements can be easily and quickly adjusted to vary the spacing of their lips 18 in respect to the retroverting edges 13 and the folder thereby adapted for the manipulation of strip material of different thicknesses. The springiness of the 40 smoothing elements 15 is obviously advantageous in that it permits yielding in the event of irregularities such as cross seams or joints, in the strip material to preclude clogging of the folder or tearing of the strip.

In the use of the folder, the edge of the body fabric F is passed into the central interval 20 between the two retroverting edges 13 where it meets the folded strip S with the latter lapped about said edge for guidance of the two together by the lateral extension 7 of the folder to the needles 5—all in the manner clearly shown in Fig. I.

- Having thus described my invention, I claim:
- 10 1. A strip folder for sewing machines and the like comprising a guide tube which merges from flat cross-sectional configuration at its receiving end into U-shaped cross-sectional configuration at its delivery end, with provision at the latter end of spaced retroverting edges about which the folded margins of the strip pass; smoothing elements in the form of spring tongues secured at one of the ends to the guide tube and having inwardly directed lips at their free ends parallel with the retroverting edges to cooperate with said edges; and means whereby the spring tongues can be separately adjusted to vary the spacing of their lips relative to the retroverting edges.
  - 15 2. A strip folder for sewing machines and the like comprising a guide tube which merges from flat cross-sectional configuration at its receiving end into U-shaped cross-sectional configuration at its delivery end, with provision at the latter end of spaced retroverting edges at an angle to the longitudinal about which the folded margins of the strip pass for directional change in the travel of the strip; smoothing elements in the form of spring tongues secured at one of their ends to opposite sides of the guide tube and having inwardly directed lips at an angle corresponding to that of the retroverting edges aforesaid and adapted to cooperate with the latter in flattening the folds of the strip and eliminatingcurls therein; and means whereby the spring tongues can be adjusted to vary the spacing of their lips relative to said retroverting edges.
  - 20 3. A strip folder for sewing machines and the like comprising a guide tube which merges from flat cross-sectional configuration at its receiving end into U-shaped cross section at its delivery end, with provision at the latter end, of spaced retroverting edges about which the folded margins of the strip pass; elements having smoothing lips rearward of the retroverting edges with respect

to the direction of strip travel for flattening the strip and eliminating edge curls therein before it is retroverted by passage around said retroverting edges; and adjusting means for varying the spacing of the lips of the smoothing elements relative to the retroverting edges. 5

4. A strip folder for sewing machines and the like comprising a guide tube which merges from flat cross sectional configuration at its receiving end to U-shaped cross section at its delivery end, 10 with provision at the latter end, of spaced retroverting edges at an angle to the longitudinal about which the folded margins of the strip pass for directional change in the travel of the strip; elements having smoothing lips rearward of the 15 retroverting edges in respect to the direction of strip travel for flattening the strip and eliminating edge curls therein before it is retroverted by passage around said retroverting edges; and adjusting means for varying the spacing of the lips 20 of said elements relative to said retroverting edges.

5. A strip folder for sewing machines and the like comprising a guide tube which merges from flat cross sectional configuration at its receiving 25 end to U-shaped configuration at its delivery end, with provision at the latter end, of spaced retroverting edges about which the folded margins of the strip pass; elements having smoothing lips rearward of the retroverting edges in respect to 30 the direction of strip travel for flattening the strip and eliminating edge curls therein before it is retroverted by passage around said retroverting edges; and independent adjusting means for varying the spacing of the lips of said elements 35 respectively relative to said retroverting edges.

6. A strip folder for sewing machines and the like comprising a guide tube which merges from flat cross sectional configuration at its receiving end to U-shaped cross section at its delivery 40 end, with provision at the latter end, of spaced retroverting edges about which the folded margins of the strip pass; elements having smoothing lips rearward of the retroverting edges with regard to the direction of strip travel, for flattening the strip and eliminating edge curls therein 45 before it is retroverted by passage around said retroverting edges.
